UNITED STATES PATENT OFFICE.

ELWOOD B. AYRES, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

Application filed July 1, 1921. Serial No. 481,794.

To all whom it may concern:

Be it known that I, ELWOOD B. AYRES, a citizen of the United States, residing in Philadelphia, Pennsylvania, have invented 5 certain improvements in Driers, of which the following is a specification.

My invention relates to certain improvements in driers, particularly for drying porcelain ware.

10 The object of my invention is to design a drier so that the ware is first subjected to air in circulation having a high humidity, then subjected to air in circulation having high temperature and low humidity, and is 15 finally cooled by air passing through an independent channel in the drier.

In the accompanying drawings:

Fig. 1 is a longitudinal sectional view of my improved drier;

20 Fig. 2 is a transverse sectional view on the line 2—2, Fig. 1; and

Fig. 3 is a sectional plan view on the line 3—3, Fig. 1, of one side of the drier.

1 is the casing of the drier shown in outline, but it will be understood that it may be made in any suitable manner. In the casing is an inner, transverse partition formed by two vertical walls 2 and 3 and a horizontal section 4. The walls 2 and 3 are spaced a 25 given distance from the front and rear ends of the outer casing, and the horizontal section 4 is likewise spaced from the bottom, as shown in Fig. 1, to form passages a, b, c. 5 is a central vertical partition stopping short of 35 the section 4 and dividing the central portion of the drying chamber into compartments d and e.

6 is an endless conveyer having carrying trays 7 for the porcelain, or other ware. The 40 trays are so arranged that they remain horizontal in passing through the drier. 8 are the upper guide wheels for the conveyer and 9 are the lower guide wheels. 10 are the lower guide wheels for the outer run of the 45 conveyer. The conveyer travels in vertical paths in the direction of the arrows.

11 is the feed opening of the drier and 12 is the delivery opening. 13 and 14 are circulating fans and in the independent heating 50 chambers 21 and 22, respectively, at the

side of the drier, are the heating pipes 15, 15^a. The vertical partition 16 separates the heating chamber from the drying chamber and is discontinued at 17 and 18 forming 55 passages for the air to return to the heating chamber from the drying chamber.

At the delivery end of the drier is an exhaust fan 19 connected by a duct 20 with the upper portion of the rear passage. The air in the compartment e is kept at about 120 60 degrees and at a high humidity, while the air in the compartment d is kept at about 175 degrees and at a low humidity so that the ware, as it enters the compartment d from the passage a, is subjected to the air at low 65 temperature and a high humidity, preventing the too rapid drying and cracking of the ware. The ware is then conveyed into and through the compartment e, where it is subjected to a comparatively high temperature 70 and low humidity. From this compartment, it is conveyed through the passage b to the delivery opening 12. Air at about 100 degrees enters the passage through this opening 12 and is exhausted through the fan 19. 75 This movement of the air cools the ware to about 100 degrees. The conveyer then travels through the lower passage c, the trays being cooled and ready to receive another load at the feed opening 11. 80

I claim:

1. The combination in a drier, of a casing; an inner transverse partition spaced from the ends and bottom of the casing forming a drying chamber and passages; a 85 transverse partition dividing the chamber into two compartments; independent means for heating the air in each compartment; independent means for circulating the air in the compartments in order that the air in one compartment may be regulated so as to be high in humidity and of low temperature, the air in the other compartment having a higher temperature and a lower humidity; and means for conveying material through the said compartments and passages.

2. The combination in a drier, of a casing; a drying chamber therein having two compartments; an independent heating chamber connected to each compartment; a 100

2. circulating fan for independently circulating the air in each compartment so that the air in the first compartment may be regulated so as to be high in humidity and low in 5 temperature while the air in the second compartment may be regulated so as to be low in humidity and of higher temperature; a

rear passage in the casing; an exhaust fan communicating with said passage so as to create a current of cold air therein; and a 10 tray conveyer passing in vertical paths through the two compartments and through the rear passage.

ELWOOD B. AYRES.
